PC(57) **CLAIM**

The ornamental design for a face mask, as shown and described.

DESCRIPTION

FIG. 1 is a front view of a face mask showing my new design; with the rear view being a mirror image thereof;
 FIG. 2 is a top view thereof;
 FIG. 3 is a bottom view thereof;
 FIG. 4 is a right-side view thereof;
 FIG. 5 is a left-side view thereof;
 FIG. 6 is a cross-sectional view taken along line 6-6 in FIG. 1; and,
 FIG. 7 is a perspective view thereof, shown in an open state. The broken lines shown represent the environment of the claimed design and form no part of the claimed design.

1 Claim, 7 Drawing Sheets(56)
